UNITED STATES PATENT OFFICE.

HARRY BERKSON, OF CHICAGO, ILLINOIS.

FOUR-IN-HAND NECKTIE.

Application filed June 3, 1927. Serial No. 196,221.

This invention relates to four-in-hand neckties and particularly to linings for the same.

The invention is fully described in the following specification and shown in the accompanying drawings, in which—

Figure 1 is a rear elevation of a necktie embodying the invention;

Fig. 2 is a similar view of the lining before it is placed in the necktie;

Fig. 3 is a partial section on the line 3 of Fig. 2; and

Fig. 4 is a partial enlarged perspective of the knot-forming end of the lining.

15 The embodiment illustrated comprises a four-in-hand necktie having a cover 5 of silk or the like which is preferably cut on the bias in a well known manner, and a lining having a converging portion 6 which lies within the 20 knot-forming portion of the tie, a band portion 7 and a slightly diverging end 8 for the small end of the tie.

Various means have been devised for giving the proper shape and body to the knot-forming portion 6 and it is believed that the 25 present invention provides a lining for such a tie which has numerous advantages over those heretofore used.

This lining consists especially of two pieces 30 of flat material 9 and 10 as shown in Fig. 4 which are preferably of substantially the same contour and which are secured together along their edges by means of lines of stitching 11 and 12. One of these pieces of lining 35 is preferably cut from a strong firm material which is substantially non-extensible under an endwise pull. This gives a great deal of strength to the tie and supplies a strength for endwise pull which is entirely lacking in 40 the cover which, as previously stated, is cut on the bias.

This lining gives the necessary strength and body to the tie without bulkiness, particularly at the edges, which would result 45 from the use of a lining which was double in thickness but in which the edges were bent back upon themselves instead of lying per-

fectly flat and being sewed together as applicant has here done.

This tie in actual practice has been found 50 to form a particularly good looking and desirable knot, and particularly free from wrinkles after it has stood sometime after being untied. This is particularly true where one of the fabric members 9 or 10 is made of 55 wool. Even where the other member is of cotton, which is particularly likely to take and hold a wrinkle, the other being of wool has a tendency to cause the cotton to return to its original flat shape.

If desired, the neck band 7 may be sewed between the upper ends of the members 9 and 10 and secured thereto as by means of lines of stitching 13.

Thus it will be seen that a particularly desirable form of necktie has been devised and one which can be manufactured easily and economically.

While I have shown and described but a single embodiment of this invention, it is to 70 be understood that it is capable of many modifications. Changes therefore in the construction and arrangement may be made which do not depart from the spirit and scope of the invention as disclosed in the appended claims.

I claim:

1. In a four-in-hand necktie, a lining having a knot portion made up of two substantially similarly shaped sections of material 80 stitched together along their longitudinal side edges only, one of said sections being composed of a nonwrinkling material and the other of a material which is substantially non-yielding on a longitudinal pull.

2. A lining for neckties consisting of two sections of fabric cut to the shape of a portion of a necktie and stitched together along their longitudinal side edges only, one of said sections being composed of wool material and the other of a material which is substantially non-yielding longitudinally.

HARRY BERKSON.
